UNITED STATES PATENT OFFICE.

JAN H. M. WALDORP, OF NYMWEGEN, HOLLAND.

APPARATUS FOR RECORDING SPEED OF TRAINS ON RAILWAY-BRIDGES.

SPECIFICATION forming part of Letters Patent No. 279,292, dated June 12, 1883.

Application filed April 10, 1882. (No model.) Patented in France February 23, 1882, No. 147,522; in Belgium February 24, 1882, No. 57,154; in England March 1, 1882, No. 990, and in Germany March 10, 1882, No. 20,401.

To all whom it may concern:

Be it known that I, JAN HERMAN MARIE WALDORP, a subject of the King of Holland, residing at Nymwegen, in the Kingdom of Holland, have invented new and useful improvements in apparatus for checking and recording the speed of trains passing over railway-bridges, gradients, and other parts of the permanent way, of which the following is a specification.

The constantly-increasing weight of the loads carried by railway-trains has latterly caused attention to be directed to the necessity of limiting the speed of such trains when passing over iron railway-bridges, in the interest of the security and the preservation of such bridges, and in some countries regulations have already been enacted in this direction, among others in the Kingdom of Holland, where the speed at which trains are allowed to pass over bridges is limited to thirty kilometers (about eighteen and a half miles) an hour.

Now, the object of this invention is to provide mechanism and apparatus for registering this speed. Such mechanism, of which the registering or recording apparatus constitutes an integral part, should, to be of any real value for the purpose for which it is intended, combine the following properties: First, the mechanism should work automatically without the intervention of the employé charged with taking off the records, as the only duty of this employé should be to see to the regular working of the mechanism and to prepare the instrument for receiving the records; second, the apparatus for receiving and making the records should be placed within the immediate reach of the said employé, and should by preference be placed in the office of the station-superintendent, and it should be inclosed in such a manner that no other person than he can touch it; third, the records should comprise a series of trains passing during a space of time—of twenty-four hours, for example—without it being necessary for the employé to touch the apparatus; fourth, the records should be such, if required, as to separately indicate the speed of the trains at various parts of the bridge. None of the apparatuses at present in use fulfill these combined conditions. They

consequently give inexact results, and therefore cannot be relied on. Some of the said apparatuses indicate the speed (notably the Boulengé system) by means of a needle moving over a dial. By observing the space passed over by the needle the speed of the train is calculated, while the needle has to be brought back to zero for the next train. Others—such as those used on the Netherland States railways—indicate the progress of the train over the bridge on a band or ribbon of paper by means of a wheel coated with ink, in a similar manner to that by which the Morse apparatus transmits telegraphic symbols; and to cause the paper band to unroll, the employé, each time a train is expected, has to put the apparatus in movement and to stop it when the train has passed. The speed is calculated by measuring on the band of paper the distance between the point where the wheel commenced to mark at the entrance of the train, and the point at which the wheel ceased to mark when the train left the bridge.

The mechanism and apparatus hereinafter described are free from the objections common to those employed until now.

The improved mechanism and apparatus may be divided into two distinct parts, videlicet: first, the mechanism or bridge apparatus on the bridge itself, consisting of a certain number of contact-points, which communicate the passage of the wheels of the train to; second, an apparatus placed in the inspector's office of the nearest station where the said contacts are recorded.

Figure 1 represents in three views the bridge apparatus, and Fig. 2 a plan; Fig. 3, a side elevation, partly in section; and Fig. 4, an end view of what I term the "station apparatus."

In the bridge apparatus (which is somewhat similar to those which the Netherland States railways have applied to several bridges) the said contact-points are applied either only at both ends of the bridge or at intermediate points, according to the length of the bridge. This apparatus is represented in the views shown at Fig. 1 of the accompanying drawings.

At a short distance above the rail, Fig. 1, is placed what may be termed a "treadle," constructed of a piece of steel, a' , on the end of a

horizontal rod, b' . When the rod b' turns the arm or link c' is moved upward, moving with it the bar d' , thereby placing the contact-plates e' e'' in contact.

- 5 From the knobs f' and f'' pass conducting-wires terminating at the station, as hereinafter described. By this means on the pressure of each wheel of the train on the treadle a' the horizontal rod b' turns, the bar d' is raised, and 10 the plate e' is put in contact with the plate e'' . A piece of india-rubber, h' , applied under the treadle, and the steel-wire spiral springs g' g'' around the bar d' , cause these two pieces to re-take their normal position after each wheel 15 has passed and established contact between the plates of copper e' and e'' .

The station apparatus is constructed substantially as follows: I employ a clock-movement operated by a spring and regulated by 20 means of a Foucault fly-pinion (with movable wings) capable of causing a shaft to make each of its revolutions in the same period of time. A cylinder follows the rotation of the said shaft, and consequently accomplishes one revolution 25 in the same time. On the said cylinder is marked the space of time which the train occupies in passing.

An arrangement of mechanism constructed as hereinafter described is employed to set the 30 clock-movement going as soon as the train reaches the bridge, and to stop it after the train has passed. An apparatus constructed as hereinafter described transmits to the cylinder the contacts which have taken place on the bridge 35 by the treadles during the passage of the train over the bridge in such a manner that the distance existing between the two contacts recorded, taken in connection with the speed of rotation of the cylinder, will indicate the time 40 the train has been on the bridge between the two treadles when these are placed at both ends of the bridge. It will be evident that in this manner by establishing several treadles the speed of the train over various parts of the 45 bridge may be checked and registered.

I will now describe the station apparatus, referring to Figs. 2, 3, and 4, similar letters in the three figures representing similar parts.

The clock-movement is constructed of an arrangement of wheel-work contained in a brass box, K K , and moved by a spring in the barrel T , which is wound up by means of the handle H . The movement of the clock is regulated by the fly-pinion V . The number of 50 seconds in which it is desired that the shaft A shall make one revolution is regulated by weighting or lightening, as may be found desirable, the fly-pinion. The shaft A extends outside the box, and is provided at one of its 55 ends with a pin, P , which serves to communicate a rotating movement to the cylinder C C , made of suitable sheet metal, and fixed on a horizontal shaft, D D , working in two supports, S S , and carrying at one of its ends a 60 small fork, v , into which takes the pin P in such a manner that the shaft A in turning moves the shaft D D with the cylinder.

Every morning, before the arrival of the first train, the cylinder is covered with paper coated with white lead, blackened over a petroleum or paraffine lamp, as hereinafter described.

The paper should be divided by appropriate lines into bands corresponding with the seconds of time required for one revolution of 75 the cylinder.

The length of the cylinder is regulated according to the number of trains to be registered on the same paper band, and will depend on the speed with which the marking 80 needle or hand, hereinafter described, passes over the cylinder.

To prepare the cylinder for registering, its shaft is taken from the support and the cylinder covered with paper, one end of which is 85 coated with gum. It is placed in a wooden apparatus—such as that shown in Fig. 5—in the supports of which the cylinder is turned, a petroleum or paraffine lamp being placed underneath, so that the paper becomes covered 90 with lamp-black. As soon as the trains which are to be registered have passed, the paper is cut and removed from the cylinder and plunged in a bath of gum-lac and alcohol for the purpose of fixing the records, Fig. 6. The 95 paper is then suspended on the wooden cross-bar of the bath to allow it to drain and dry.

I will now describe the apparatus for starting and stopping the clock-movement.

When a train comes on the bridge each 100 wheel, as has been already described, presses on the treadle and causes the two plates e' and e'' to make contact. These plates communicate by means of a conducting-wire with an electromagnet consisting of two bobbins, E E , on a 105 core of soft iron, over which is placed the armature or anchor M . An electric current will thus be set up, which, passing through the bobbins E E , and communicating with the soft-iron core, will attract the anchor or armature M , the tail B B of which, as the armature turns on the axis a a , will thereby be raised. The tail B B presses on the under side of one of the arms of the lever h h h , made of the form shown in Fig. 4 of the drawings, such 115 lever turning on a small horizontal pivot, d d . The said lever-arm is provided with a small sliding counter-weight, g , and with a catch, m , in the form of a knife, and the end of the lever presses on the side of the spring G , which is attached to the horizontal shaft F F . The other arm of the lever terminates with a stop-button, i , which, in the position of the lever shown in the drawings, presses an ebonite plate, P' P' , forming part of the vertical shaft 120 of the fly-pinion V .

To the same support which carries the small arbor d d of the lever is fixed, near the point n , the pivot of the small curved rod l l , the elbow of which presses under the hereinbefore described arm under the bend of the lever h h . The said lever, with its accessories, has for its object the starting and stopping of the clock-work. The parts being in the position shown 125

in the drawings, and the spring in the barrel being wound up, the movement of the clock-work may be stopped by pressing the button *i* against the ebonite plate of the fly. In all 5 cases as soon as the anchor or armature *M* is attracted the tail *B* thereof raises one of the arms of the lever, which causes the part *i* to descend in such a manner that the fly becomes free and the wheel-work commences to move. 10 The fall of the lever into its normal position by the breaking of the current and the release of the anchor or armature is prevented by the pressure of the end of the lever-arm against the spring *G*.

15 The stoppage of the clock-work is produced in the following manner: After one revolution of the shaft *A*, the pin *q*, being on the wheel of this shaft, throws off the small curved rod or striker *l*, from which it follows that the movement of this latter raises one of the arms of the lever near the bend, detaches the other arm from the spring *G*, and presses the knob *i* against the ebonite plate. At the same time the catch *m*, in the form of a knife, falls into 20 the notch of a small wheel, *m'*, fixed on the same shaft, *A*.

The records on the cylinder are produced as follows: The shaft *A*, as hereinbefore described, communicates its rotary movement to the cylinder *C*, against which is placed the needle *o*, constructed of a small plate of steel of a pointed form inclined toward the cylinder and attached to a small vertical brass rod, *w w*, which, with the small pin *t*, forms an anchor 30 or armature opposite the electro-magnet *e e*, (constructed of two bobbins having cores of soft iron and wound with wire,) attached to a brass carriage, *f f*, which moves on the conducting-shafts *r r' r' r'*, fixed in the supports *O* 35. O. The carriage can be turned a quarter of a revolution on the shaft *r' r'*, in order to allow, when required, the removal of the cylinder *C*. At the same time that the current passes through the large bobbins *E E* it also passes 40 through the small bobbins *e e* by the agency of the brass pieces *N N'*, by means of which the anchor or armature *u t u*, with the needle *o*, is attached, and then set free by the breaking of the current, thereby communicating a to- 45 and-fro movement to the needle *o*. In addition to this to-and-fro movement, the needle has also a forward movement, when the clock mechanism works, in consequence of the carriage being on the one side drawn by means of a cord, *x' x'*, and a spring (not shown) within 50 a barrel, *z*, and on the other side it is retarded by the cord *x x*, wound on the shaft *L* by means of the vertical pulley *Y*. When the clock-work goes, the cord *x' x'* is wound up, 55 and the cord *x* is unwound. When the hand reaches the end of the cylinder and the records have been made, it is necessary, in order to make fresh records, to bring back the carriage to the commencement of the cylinder by winding the cord *x* on the shaft *L*, which can be 60 turned independently of the shaft of the clock-work, and the return movement of which is

prevented by a catch. As the paper on the cylinder *C* is divided into as many bands as there are seconds of time in one revolution, it 70 will be evident that the rotation of the cylinder and the to-and-fro movement of the hand commence simultaneously. At the same time the number of oscillations produced by the hand or needle on the paper corresponds with the 75 number of wheels which have passed the point of contact.

The operation of the apparatus is as follows: The hereinbefore-described contact-plates on the bridge are connected by the conducting-wires with the battery and with the bobbins *E E* and *e e*, in the manner represented in the drawings. Supposing the parts to be in the position shown in the drawings, the current from the battery is interrupted as many times 80 by the contact-plates of the first treadle as by those of the second treadle on the bridge. At each pressure of the first wheel on the first treadle placed at the commencement of the bridge the current by the contact of the two 85 contact-plates passes to No. 1 treadle, (not to No. 2 treadle,) reaches the piece *N*, whence it passes through the bobbin of the small electro-magnet *e e*, then passes through those marked *E E*, and returns by the piece *N* to 90 the other pole of the battery. During the passage of the current the cores of the bobbins *E E* and *e e* are magnetized, and consequently the anchors or armatures *M M*, and *u t u* (the pin) are simultaneously attracted. 95 The effect of the attraction of the first anchor or armature is that one of the arms of the lever is raised, the fly *V* is set free, and the clock-movement commences to work. The cylinder *C* turns and the carriage *f f* is set in motion. 100 Moving along the shafts *r r' r'*, the attraction of the anchor or armature *u t u* causes the hand or needle to oscillate over the paper on the cylinder. The passage of each wheel over the first treadle imparts an oscillating motion to 105 the needle or hand. After the passage of the last wheel the needle or hand passes along the cylinder until the first wheel reaches the second treadle, when it again commences to oscillate. After the passage of the last wheel 110 over the second treadle the needle or hand drags until the shaft *A* (and consequently the cylinder also) has completed a revolution, at which moment the pin *q* reverses the small rod *l*, which raises the arm of the lever placed 115 above, and retains the fly-pinion by its pressure on the ebonite plate in such a manner that the clock-work is stopped. At the same time the lowering of the other arm of the lever causes the catch *m* in the form of a knife to fall into 120 the notch of the wheel and the end of the arm is released from the spring *G*. The hand or needle which, by its movement on the revolving cylinder will describe a helicoidal line, returns after one revolution of the cylinder to 125 the same line, forming its point of departure, and is ready to commence its operation for the next train.

It will be evident that in place of obtaining

the measure of the records by means of bands on the paper, the same result may be (and is by preference) obtained by measurement, the circumference of the cylinder being known, 5 and also the number of seconds occupied in a revolution.

The cylinder should be constructed in such a manner that the number of seconds required for one revolution should be equal to a full 10 number of millimeters, so that by measuring the length of the line marked in millimeters, the number of seconds will be at once known.

The apparatus to be employed in the station-office is inclosed in a case with glass sides, 15 which is locked by a key.

The handle of the drum or barrel T should be extended so that the knob should be outside the case, which will enable the attendant to wind up the clock-work twice a day in order 20 to insure a regular action of the spring in the barrel.

The barrel and spring may be replaced by a weight, whereby a more regular action of the 25 clock-work would perhaps be obtained. Further, an opening (closed by a sliding or hinged lid) should be made in the upper side of the case above the cylinder, in order that the inspector may be able to mark by means of a hand or needle the number or letter of the train 30 which has passed, by which means all danger of removing the lamp-black from the paper or of blurring or staining it will be avoided.

Although the invention has been described as applied to a railway-bridge, it is evident that 35 it is equally applicable to gradients and other parts of the permanent way.

Having now described the nature of my said invention and the manner of performing the same, what I claim is—

40 1. The mechanism as described and as shown in Fig. 1, consisting of the combination of the parts a' b' c' d' , the reacting-springs g' g'' , contact-plates e' e'' , and conducting-wires adapted to be located at both ends of a bridge, and making contact each time that the wheel of a train 45

passes it, and by its touching closing an electric current, into which the apparatus for controlling at the station-house is linked or connected, and where the contacts are communicated and noted, all substantially as described. 50

2. The described clock-work mechanism for giving to the axle a regular periodical rotating motion, consisting of a wound incased spring, shaft A, pin P, and fork v, these parts being combined and operating as set forth. 55

3. The cylinder C, arranged to be removed, with its shaft D, from its supports S S, and to be replaced therein for the purpose set forth, in combination with the fork v on said shaft, and with the pin P, connected to the shaft A 60 of the clock mechanism, the combination being and operating substantially as set forth.

4. The combination, substantially as described, for setting the clock-work in motion as soon as the train comes on the bridge, and 65 for arresting it after the train has passed by, consisting of the contact-plates e' e'' and their described operating devices, conducting-wire, electro-magnet E E, armature-lever M B, lever h, counter-weight g, catch m, notched plate m', 70 spring G, button i, plate P, fly V, rod l, and pin q.

5. In combination, the rotating cylinder C, needle o, rod u u, and pin t, forming an armature, carriage f, shafts r r', and electro-magnet 75 e e, substantially as and for the purposes set forth.

6. The combination of the described mechanism on the bridge, having contact-points for communicating the fact of the passage of the 80 car-wheels, with the described apparatus in the station office, where the said contacts are recorded, consisting of the clock mechanism, substantially as described, and a marking-cylinder operated thereby, the combination being and 85 operating substantially as set forth.
